Aug. 22, 1833.

William Schubert & T. Hill's "Inventors"
of Hagerstown, State of Maryland.

Letters Patent.

Aug. 22, 1833

The schedule referred to in these Letters patent and making part of the same containing a description in the words of the said William Schubert and Thomas Schubert themselves of their improvement for cutting grain, grass, &c.

To all to whom these presents shall come,
Be it known that we William Schubert and Thomas Schubert
of Hagerstown in the County of Washington and State of
Maryland, have invented a new and useful improvement
in cutting grain, seeds, & grass, and that the following
is a full and exact description of the construction, and
operation of said machine as invented by us - and titled the
oil and shear grain cutter.

This machine is to be made of
suitable materials of the following dimensions. The frame or
ground work to be from ten to twelve feet in length, and from
three to nine feet in breadth connected together by cross pieces,
one, twenty two inches in rear of the front ends, one, four feet six
inches in rear of the first, one, two feet six inches in rear of
the second, and one at the extreme end of the frame from the
second to the third, likewise a cross piece or a bear block for
the uprights and perpendicular shaft to work upon, The said
cross pieces to be divided into equal spaces of three or four inches
each, every division of which to be covered upon the inside
of, and kept upon by four iron plates, one placed on each
cross piece, and the iron plates to be from three to four inches

7724

are made over the edges of the bottom ones and likewise to be
upholster with in length corresponding with the bottom one
and curved to a point presenting the shape of a spear, a rivet
hole to be made in it to suit the bottom one by which they
are to be fastened together in a manner to suffer them to play back
wards and forwards, like a common pair of shears so that
when the one hand is shut the other stands open to receive the
other presenting a shape or force of an acute angle, the edge
of the top blades to be made similar to a common pair of
shears the handles of all the top blades, are to continue back
so near of the crop pieces from one to two feet, two of which are to be
continued so far back, as to pass the perpendicular shaft, a proper
distance having them duly connected together by a crop piece so
as to permit them to play freely when in motion, the arms
or handles of each to be made proportionally strong short
shorter ones are likewise to be connected to the longer, as that
when motion is given to the finger the whole moves regularly
together, The seat is to be made of suitable material of
the following dimensions, to be as wide as the space between
the uprights upon which it revolves, with four arms turned
in each end of the shaft at equal distances apart, each
arm to be from two to four feet in length, at the end of
each arm a segment corresponding with the circle which
the seat will describe with the arms in it, is to be fastened
from eighteen to twenty four inches in curve length from
one segment to the opposite one, this is to be put on a suit-
able pair of board or otherwise fitting the curve or
arch of each, and likewise on each segment, these forming
the seat, which in its shape, resembles a cylinder, or
drum with four open ends, and four uprights, which
may be increased to a greater number, or reduced to a less,
as the case may require, the top of the seat is to be
joined with the back and the back with the arms

in front. The space between the first and second crop pieces is to be occupied by the scything plains or sheet. The space between the second and third crop pieces to be occupied by the wheel, which are to carry the machine, and to give motion to the wheel. The space behind the wheels, for purposes as the case may require immediately, or upon a line with the first crop piece, a perpendicular is to be raised on each side of the frame from two to four feet in height, of proper strength, with braces to keep them permanent, which are intended to give bearings to the guides of the reel shafts.

In rear of the space for the scything plains or sheet a guard board, is to be raised, to give proper direction to the grain and to be of proper height. In the centre of the space, in which the wheels move, two uprights are to be raised, one on each side of the frame, of proper height and connected together, by a cap or head block, through which the perpendicular shaft is to pass. The upright to be raised to give strength and support to the frame. The shears are to be made of suitable materials, of the following shape and dimensions, the bottom plates are to be made with two blades running out eighteen inches. in length, ears of the rivet plates, to which they are connected and which is to be made of a proper breadth, to suit the crop piece to which they are fastened, the blades that run out, are to be set so far apart as to have a space of three or four inches between them, more or less to suit or correspond with the space which are to receive the grain. The inner edges of each blade or bottom plates to be made similar to that of a common pair of shears, and of proper breadth, to receive bolt holes, by which they are to be fastened to the projecting pieces which are to be brought to a point in front of the plates for the purpose of turning the grain and passing the machine into the field. The top of the reel shaft, which forms the head of the machine, is to be made of a rough timber, so as to be able to hold the grain.

which has been already described must have a pulley on
 the end next to the grain board and to stand directly opposite
 to the hand wheel or pulley on the horizontal shaft. This anchor
 is to be propelled by a horse or horses, hitched to a pair of dogs
 which are to be attached to the side of the same, the wheels
 are to be made of suitable materials and proper height, having
 such a separate spindle or shaft permanently fixed in their
 centers, so that when the wheels revolve or turn the spindle,
 or shafts are made to do so likewise. the bearing of each to
 rest upon the side frames, and center or top piece or head block of
 the perpendicular shaft on the end of one of the spindles, or
 shaft next to the center head block, thus is a cog wheel of
 proper size, and shape interlocking the one on the perpendicular
 shaft giving motion to it - the arm thereon striking the
 and ^{up} the bears giving motion to them, the segment above
 the cap, on the same shaft interlocks the open wheel, on
 the horizontal shaft at every round or revolution giving motion
 is that a strap or chain, or otherwise connect the pulley at
 the other end with the pulley on the end of the roller, give
 motion to the revolving sheet or plane at intervals, the roller
 receives its motion from the same grain wheel by means of
 a strap and pulley or chain or line of shaft as the case may
 require, the motion of the roller, gives motion to the roller
 then by the movement of the horse or horses, the roller is put
 into regular motion. The principle is made of in operation
 as follows. The propeller divides the grain as the machine
 advances, and directs it into the open, or opening made by
 the other moving sheet or the roller, and assists in carrying
 the grain in a proper position to be cut by the shears, after
 leaving the grain and passing to the roller, the roller
 and the propeller together, the end of the grain being
 cut and falling, the grain is carried by the roller
 and propeller down to the shears.

177
and the grain and stalks open a space on the
bottom of the roller, when it is done, the grain is
thus rolled in these spaces of the roller and the surface
of the stalk which are so small as to keep them as tight as
is possible a bag for carrying it in the hand of the man
to catch him if it is by the strength of the spring which
the roller moves upon to the rolling place, or when taken
in basket or the receiver before the roller, when the sur-
face of the roller leaves the surface of the roller, the grain falls
upon the receiver and remains in this position until the grain
enters the roller, then it is moved a part off as tight as
with the strength of the man upon the receiver, by the rolling
place, so that, or only so far off, and as given with
power by the use of the machine in rolling of grain —
We therefore claim the right of the invention of the roller
of open spaces, and their surfaces — The small openings
the roller rolling on spring — The rolling place or hand
or receiver — The projection or sides of the grain as above
described was intended to be used for the purpose of cutting
all kinds of grain such as, & grass, &c
